Primary Examiner — Austin Murphy(74) *Attorney, Agent, or Firm* — Lee & Hayes, P.C.(57) **CLAIM**

The ornamental design for a button device, as shown and described.

DESCRIPTION

FIG. 1 is a top perspective view of a button device;

FIG. 2 is a left-side view thereof;

FIG. 3 is a right-side view thereof;

FIG. 4 is a front view thereof;

FIG. 5 is a back view thereof;

FIG. 6 is a top view thereof; and,

FIG. 7 is a bottom view thereof.

The dashed broken lines depict portions of the button device that form no part of the claimed design.
